US00D683736S

(12) **United States Design Patent**
Goldstein et al.

(10) **Patent No.:** **US D683,736 S**
(45) **Date of Patent:** **** Jun. 4, 2013**

(54) **DISPLAY SCREEN WITH GRAPHICAL USER INTERFACE**

(75) Inventors: **Adam Julian Goldstein**, San Francisco, CA (US); **Steven Ladd Huffman**, San Francisco, CA (US); **Andre Yurievich von Houck**, San Francisco, CA (US); **Sacha Greif**, Paris (FR)

(73) Assignee: **Hipmunk, Inc.**, San Francisco, CA (US)

(**) Term: **14 Years**

(21) Appl. No.: **29/383,570**

(22) Filed: **Jan. 19, 2011**

(51) **LOC (9) Cl.** **14-04**

(52) **U.S. Cl.**

USPC **D14/485**

(58) **Field of Classification Search**

USPC D14/489, 490, 491, 492, 488, 487, D14/485, 493, 494, 495; 715/835, 848, 202, 715/205, 723, 700, 724, 725, 726, 841, 701, 715/702, 703, 704, 867, 866, 849, 850, 836, 715/837, 838, 839, 840, 842, 843, 844, 710, 715/711, 712, 201; D19/6; D20/11, 23, 37; 707/709, 219

(57) **CLAIM**

The ornamental design for a display screen with graphical user interface, as shown and described.

DESCRIPTION

FIG. 1 is a face view of a display screen with graphical user interface showing our new design;

FIG. 2 is a face view of a first modified embodiment thereof;
FIG. 3 is a face view of a second modified embodiment thereof;

FIG. 4 is a face view of a third modified embodiment thereof;
FIG. 5 is a face view of a fourth modified embodiment thereof;

FIG. 6 is a face view of a fifth modified embodiment thereof;
FIG. 7 is a face view of a sixth modified embodiment thereof;
FIG. 8 is a face view of a seventh modified embodiment thereof; and,

FIG. 9 is a face view of an eighth modified embodiment thereof.

Subject matter shown in broken lines, including all text, forms no part of the claimed design.

UNITED STATES PATENT AND TRADEMARK OFFICE
CERTIFICATE OF CORRECTION

PATENT NO. : D683,736 S
APPLICATION NO. : 29/383570
DATED : June 4, 2013
INVENTOR(S) : Goldstein et al.

Page 1 of 1

It is certified that error appears in the above-identified patent and that said Letters Patent is hereby corrected as shown below:

On the title page

Item (56) under "Other Publications", line 4, delete "B," and insert --B.,--, therefor

Under "Description", line 12, delete "and," and insert --and--, therefor

On page 2, in column 2, item (56) under "Other Publications", line 4, delete "M," and insert --M.,--, therefor

On page 2, in column 2, item (56) under "Other Publications", line 5, after "Design", insert --"--, therefor

On page 2, in column 2, item (56) under "Other Publications", line 5, delete "Report" and insert --Report--, therefor

On page 2, in column 2, item (56) under "Other Publications", line 6, delete "Author :" and insert --Author:--, therefor

On page 2, in column 2, item (56) under "Other Publications", line 7, delete "Date :" and insert --Date:--, therefor

On page 2, in column 2, item (56) under "Other Publications", line 8, delete "J," and insert --J.,--, therefor

On page 2, in column 2, item (56) under "Other Publications", line 12, after "Machine", delete ", p. 58", therefor

Signed and Sealed this
Eighteenth Day of November, 2014

Michelle K. Lee
Deputy Director of the United States Patent and Trademark Office
